UNITED STATES PATENT OFFICE.

KENTON CHICKERING, OF OIL CITY, PENNSYLVANIA.

CASING OR TUBING ELEVATOR.

SPECIFICATION forming part of Letters Patent No. 730,233, dated June 9, 1903.

Application filed February 3, 1902. Serial No. 92,380. (No model.)

To all whom it may concern:

Be it known that I, KENTON CHICKERING, a citizen of the United States, residing at Oil City, in the county of Venango, State of Pennsylvania, have invented certain new and useful improvements in Casing or Tubing Elevators; and I hereby declare the following to be a full, clear, and exact description of the same, reference being had to the accompanying drawings, in which—

Figure 1 is a perspective view of a casing or tubing elevator embodying my invention, the jaws or clamp closed as when in use. Fig. 2 is a top plan view of the same, the bail-links or reins being in section. Fig. 3 is a vertical section of the elevator, the section being taken on the lines 3 3 3 3, Fig. 2. Fig. 4 is a sectional view of a portion of the jaws or clamp, the tie-link, and its spring-latch.

Like symbols refer to like parts wherever they occur.

My invention relates to that class of devices employed for raising, lowering, and drawing well tubing or casing, comprising reins or bail-links, clamps, or jaws for seizing the casing or tubing, and means for locking the clamp or jaws when closed upon the tubing or casing, and, while generally applicable for use with all classes of tubing or casing, has been especially devised as an elevator for "flush-joint" casing or tubing—that is to say, such tubing as is devoid of flanges, sleeve-couplings, or thimbles.

To this end the main feature of my invention embodies the combination, in a casing or tubing elevator, of pivoted jaws having a plurality of converging inclines on their interior, included serrated wedge slips or wickers, and means for locking the pivoted jaws, whereby the tube or casing may be seized and held while raising or lowering the same.

A second feature of my invention embraces the combination, in a tubing or casing elevator, of pivoted jaws having a plurality of converging inclines on their interior, included spring-supported wedge slips or wickers, and locking mechanism for the pivoted jaws, whereby the elevator may adjust itself to pipes of different diameters.

A third feature of my invention embraces the combination, in a tube or casing elevator, of pivoted jaws having a plurality of converging

inclines on their interior, included spring-supported wedge slips or wickers, devices for adjustably limiting the travel of said slips or wickers, and means for locking the pivoted jaws of the elevator, whereby the elevator may be set or adjusted to tubes of different diameters.

There are other minor features of invention, all as will hereinafter more fully appear.

I will now proceed to describe my invention more fully, so that others skilled in the art to which it appertains may apply the same.

In the drawings, A and B indicate the pivoted sections or jaws of a tubing or casing elevator, and C C' the reins or bail-links by which the elevator is suspended, one of said bail-links C being pivoted on the pivot-lugs *a* of the jaws and the other bail-link C' being pivoted on and forming the lock of the locking-lugs or locking-arms *b* of the jaws.

In order that the jaws may open freely when the bail-links C C' are lowered, one link-slot in each of the corresponding pivot-lugs and locking-lugs is formed as a recess or open slot, as indicated more clearly in Fig. 3, and in order that the bail-link C' (which forms the lock) may also insure the apposition of the locking arms or lugs *b* the said locking arms or lugs are slightly tapered horizontally from within outwardly, as will be noted by reference to Fig. 2.

The pivoted jaws A and B are recessed on their interior to form a plurality of converging inclined seats 1 for a plurality of wedge slips or wickers 2, so that said slips or wickers will move to and from the axis of the clamp accordingly as they move down or up said inclines.

2 2 indicate a series of slips or wickers serrated upon their inner or curved faces and adapted to bite upon an included tube or casing. Said wickers are supported from below by spring-pins (or spring-supported pins) 3, let into the shoulder 4 on the interior of the jaws A and B, so that the wickers are free to move downward and inward, while their upward travel is limited, controlled, and adjusted by means of set-screws 5 or equivalent devices which are let into the upper faces of the jaws A and B and project down into the slip-seats of the elevator.

In order to prevent the displacement of the

slips or wickers when the pivoted jaws A and B are open, the slips 2 2 are secured by headed pins or screws 6, which extend thereinto through elongated slots 7, the exterior walls of the jaws at such points being parallel with the inclines 3, as at 8, to prevent any binding of the slips or wickers 2 2 in their downward travel.

The lower ends of the reins or bail-links C C' are drawn in, as at 9, so as to embrace closely the pivot-lugs *a* and locking-lugs *b*, and at said points are encircled by tie-links 10, which prevent the spreading of the lower ends of the bail-links and support the jaws 15 under lateral strains. These tie-links 10 may be fixed in position by set-screws 11, and the one on the bail-link of the locking arms or lugs is or may be provided with a spring bolt or latch 12, the lower end of which enters an elongated keeper-slot in the upper surface of the lockings-lugs or locking-arms *b*. Such a construction will permit the limited movement of the bail-link incident to the swaying of the elevator, and will at the same time 25 prevent such movement of the bail-link as would tend to release the jaws.

The construction of the casing or tubing elevator being substantially such as hereinbefore set forth, the devices will operate as follows: The set-screws 5 are adjusted to depress the slips or wickers 2, causing the same to move down the converging inclines 1 and inward toward the axis of the clamp until the interior diameter of the clamp corresponds 35 with the casing or tubing to be raised or lowered. The jaws A B are then separated, the tube or casing introduced, the jaws closed, the bail-links C C' raised to lock the jaws, and the power applied. As the load is brought 40 on the slips or wickers 2 2 they tend to move down the converging inclines 1 1, and thus increase their grip or bite on the tubing or casing in proportion to the increase of the load or power. As soon as the load is withdrawn, 45 the spring-pins 3 react and cause the rise of the slips or wickers, so that they release the tubing or casing and permit a change of grip or the removal of the tubing or casing at the will of the operator.

Having thus described my invention, what I claim, and desire to secure by Letters Patent, is—

1. In a casing or tubing elevator, the combination with a clamp comprised of a plural-

ity of pivoted jaws and means for locking the same, said jaws having converging inclines on their interior, of a plurality of wedge-shaped serrated slips or wickers for each jaw, said slips or wickers concentrically arranged and movably connected with their respective jaws, substantially as and for the purposes specified.

2. In a casing or tubing elevator, the combination with a clamp comprised of a plurality of pivoted jaws and means for locking the same, said jaws having converging inclines on their interior, of a plurality of yieldingly-supported wedge-shaped serrated slips or wickers for each jaw, said slips or wickers concentrically arranged and movably connected with their respective jaws, substantially as and for the purposes specified.

3. In a casing or tubing elevator, the combination with a clamp comprised of a plurality of pivoted jaws and means for locking the same, said jaws having converging inclines on their interior, of a plurality of wedge-shaped serrated slips or wickers concentrically arranged and movably connected with their respective jaws, and adjustable means for varying the limit of the upward movement of the wickers in the clamps, substantially as and for the purposes specified.

4. In a casing or tubing elevator, the combination with pivoted clamp-jaws having a plurality of converging inclines on their interior, of a plurality of included and spring-supported slips or wickers, a plurality of set-screws in the upper part of the jaws for limiting the upward travel of the slips or wickers and means for locking the clamp-jaws, substantially as and for the purposes specified.

5. In a casing or tubing elevator, the combination with pivoted clamp-jaws having locking-lugs provided on their upper surface with a keeper-slot, of a bail-link which encloses the locking-lug, a tie-link for said bail-link and a latch movably mounted on the tie-link, substantially as and for the purposes specified.

In testimony whereof I affix my signature, in presence of two witnesses, this 1st day of February, 1902.

KENTON CHICKERING.
